UNITED STATES PATENT OFFICE

LOUIS H. RODDIS, OF WASHINGTON, DISTRICT OF COLUMBIA

COMBINED POCKET FLASH LIGHT AND KEYHOLDER

Application filed April 7, 1930. Serial No. 442,227.

This invention relates to pocket flashlights and key holders and has for its primary object, the provision of means which will contain a flashlight and support a plurality of 5 keys whereby the desired key may be selected in the dark and at the same time illuminate the lock, so that the selected key may be easily and quickly inserted in the key hole of the lock.

10 Another object of this invention is the provision of a combined pocket flashlight and key holder of the above stated character which will be simple, durable and efficient and which may be manufactured and sold at 15 a comparatively low cost.

With these and other objects in view as will become more apparent as the description proceeds, the invention consists in certain novel features of construction, combination and 20 arrangement of parts as will be hereinafter more fully described and claimed.

For a complete understanding of my invention, reference is to be had to the following description and accompanying drawings 25 in which:

Figure 1 is a side elevation illustrating a combined pocket flashlight and keyholder constructed in accordance with my invention.

30 Figure 2 is a side elevation partly in section illustrating the mounting of the flashlight and the key holder together.

Figure 3 is an end elevation illustrating the device.

35 Figure 4 is a similar view illustrating the opposite end of the device from that shown in Figure 3.

Referring in detail to the drawings, the 40 numeral 1 indicates a case constructed from any material suitable for the purpose and has one end fully open to receive a flashlight 2 of a well known construction. The flashlight is of the type provided with a hinged cover 3 carrying an electric light bulb 4 adapted to be 45 illuminated when the cover 3 is in an open position as shown in Figure 1 and to be extinguished when the cover is in a closed position. The case 1 may be constructed of leather or any other suitable material and has its edges stitched or otherwise secured together.

A plate 5 is secured to the case 1 adjacent the open end and has formed thereon a barrel or cylindrical shaped portion 6 to receive a pintle or shaft 7. A plurality of key hooks 8 are mounted on the shaft or pintle 7 and 55 move through slots formed in the barrel 6 whereby a number of keys may be supported to the case 1 and relative to the flashlight that they will be illuminated when the cover 3 is swung to an open position thereby permitting a person to easily select a desired key from the group of keys in the dark. With the proper key selected, the rays of light from the electric lamp 4 may be directed onto the lock so that the respective key may be easily 60 inserted in the key hole. It is to be noted that this device is extremely simple and compact so that it may be conveniently carried in one's pocket and easily handled when desiring to select a certain key and illuminate 65 the key hole of a lock.

While I have shown and described the preferred embodiment of my invention, it will be understood that minor changes in construction, combination and arrangement of parts 75 may be made without departing from the spirit and scope of the invention as claimed.

Having thus described my invention, what I claim is:

A combined pocket flashlight and key 80 holder comprising a casing having one end open, a plate secured to the casing adjacent the opened end, a pintle journaled to the plate, hooks carried by the pintle to support keys to the casing adjacent the open end, and a flashlight mounted in the casing with the illuminating part thereof exposed by the open end of said casing to permit a key hole 85 to be illuminated and the illumination of the keys that a key may be selected for insertion 90 in the key hole.

In testimony whereof I affix my signature.
LOUIS H. RODDIS.
